(57) **CLAIM**

The ornamental design for a vehicle turn signal lamp, as shown and described.

DESCRIPTION

FIG. 1 is a front perspective view of a vehicle turn signal lamp illustrating the new design;

FIG. 2 is front view thereof.

FIG. 3 is left side view thereof.

FIG. 4 is right side view thereof.

FIG. 5 is rear view thereof.

FIG. 6 is top view thereof; and,

FIG. 7 is bottom top view thereof.

The lamp in use is viewable only from the front. In all of the foregoing drawings; dashed lines are exemplary of hidden lines, intended to illustrate shape and contour and are not part of the design.
